UNITED STATES PATENT OFFICE.

WALTER N. VANCE, OF CHICAGO HEIGHTS, ILLINOIS, ASSIGNOR TO DURAND STEEL LOCKER CO., OF CHICAGO, ILLINOIS, A CORPORATION OF ILLINOIS.

COMBINATION-LOCKER.

1,307,712.

Specification of Letters Patent. Patented June 24, 1919.

Application filed February 15, 1919. Serial No. 277,226.

To all whom it may concern:

Be it known that I, WALTER N. VANCE, a citizen of the United States, residing in Chicago Heights, in the county of Cook and 5 State of Illinois, have invented a new and useful Improvement in Combination-Lockers, of which the following is a specification.

This invention relates in general to lockers 10 and has more particular reference to locker sets wherein a small individual locker is provided for the individual use of each user and a single large locker provided for their conjoint use; that is to say, in a set there 15 will be a small locker for each user adapted to receive the hat, pocketbook and other small articles of value, and in the set there is included also a larger locker adapted to receive the coat, etc., the smaller lockers being only opened by a particular combination or key in the sole possession of its user, and the larger locker being opened by any 20 one of the users of the smaller lockers. The invention, however, has as will be manifest, 25 other valuable uses.

The principal object of the invention is the provision of a locker of this group or set type in which each of the small lockers will be provided with individual locks operable only by the particular person to whom the particular small locker is assigned, and in which the large locker may be operated by any of the occupants of the 30 small locker upon a mere unlocking of the individual small locker and without requiring that the door of the small locker be opened; so that any individual having one of the smaller lockers may by merely unlocking its lock and manipulating the lock 35 of the large door opening device, open the large locker.

I am aware that in the past lockers of this general character have to some extent been constructed, but the means for unlocking 40 the door of the large locker has been located within the several small lockers, so that it has been necessary not only to open the door of a small locker before the door of the large locker could be opened, but also to reach in 45 and manipulate a door latching mechanism located conveniently within the locker.

My present invention has for its object the more convenient manipulation of the larger door controlling devices and the increase 50 of the effectual capacity of the small

lockers by relieving the necessity for always leaving sufficient room in the small lockers to permit manipulation of the door of the large locker.

The invention has numerous other and important advantages, as for example the provision of a simple sturdy construction which may be cheaply manufactured and not be likely to require frequent repair or replacement and which will be pleasing in appearance and easily understandable in operation. 60

Numerous other objects and advantages of the invention will be apparent as it is better understood from the following description when considered in connection 70 with the accompanying drawing illustrating a preferred embodiment thereof.

Referring to the drawing,

Figure 1 is a front elevation of a set of lockers embodying my invention. 75

Fig. 2 is a side elevation of same.

Fig. 3 is an enlarged partial front elevation of a portion of the locker showing certain details of construction. 80

Fig. 4 is a section taken substantially on the line 4—4 of Fig. 3.

Fig. 5 is a partial vertical sectional view taken substantially on the line 5—5 of Fig. 3.

Fig. 6 is an enlarged perspective of one of the large locker door controlling slides. 85

Fig. 7 is an enlarged partial front elevation showing the construction of the arrangement at the top of the locker where two small lockers are provided.

Fig. 8 is a section taken substantially upon the line 8—8 of Fig. 7. 90

Fig. 9 is a section taken substantially on the line 9—9 of Figs. 1 and 7.

Fig. 10 is a partial rear elevation of the structure employed in the present instance 95 to be controlled conjointly by the locks of the two upper small lockers.

Fig. 11 is a section taken substantially on the line 11—11 of Fig. 10.

Fig. 12 is a detail perspective view of the 100 swinging member, and

Fig. 13 is a similar view of the slide for the upper lockers.

For the purpose of illustrating my invention I have shown on the drawing a locker 105 set consisting of the large locker generally indicated at 21, and seven small lockers six indicated generally at 22 being located in a vertical column at one side of the set, and the other, the seventh indicated at 23 being 110

located above the large locker. The doors of the lockers are hinged in any usual or preferred manner at 24 and 25 to side members of the frame or body 26 of the set and 5 swing from and toward a facing 27 located at or in front of the vertical partition between the large lockers and the column of small lockers.

Referring more particularly to Figs. 8. 10 and 9 it will be noted that the central partition consists of a sheet metal wall 28 fast to a flange 29 of an angle member 31 forming a portion of the facing, a second angle member 32 being provided and having also an 15 inwardly extending flange 33 as shown. The flange 29 is provided with slots 34 one located adjacent each door of a smaller locker and through each of these is adapted to extend a lock bolt 35 of a lock 36 of either the 20 key or combination type, provided to lock the small locker in closed position. And a similar slot 37 is provided through the flange 33 opposite the small locker 23 above the large locker. The large locker is provided with a sheet metal door 38 having an 25 angle iron framework, only a part of which is shown in Fig. 4 in section one flange 39 of the angle iron at the free side being secured to one face of the door and the other 30 41 extending inwardly parallel to and spaced from the flange 33 already mentioned. The flange 41 is stamped to provide a lip or offset 42 extending into the space between the flanges 33 and 41 and mounted upon the 35 opposite face of the flange 33 is a vertical sliding lock bar 43 held as indicated in Fig. 3 against its face by pins 44 extending through slots 45 in the lock bar. At intervals and adjacent the several lugs 42 lugs 46 40 are stamped from the lock bar 43 and these are bent inwardly at 47 and then downwardly at 48 to provide locking portions 49. The portions between the points 47 and 48 extend through slots 51 in the flange 33, thus 45 disposing the locking portions 49 in operative relation with the lugs 42.

Viewing Fig. 3 it will be noted that upon lifting of the lock bar, the locking portions or lugs 46 will be lifted clear of the lugs 42 and the door of the large locker may be 50 opened. The lugs are beveled as indicated at 52 and 53 so that the closing of the large door after it has been unlocked and opened will result automatically in the reengagement 55 of the locking parts 49 and the lugs 42 unless the lock bar be held in elevated position. A number of handles or manipulating devices 55 for lifting the lock bar are provided upon the outside of the facing 27 and the connection 60 between these manipulating devices and the lock bar is such that if any one of the manipulating devices be raised, the lock bar will be correspondingly lifted while the other several manipulating devices may 65 remain at rest. Means are provided for re-

straining this lifting of the manipulative devices when the small lockers are locked, which means become instantly inoperative with respect to the particular manipulative device if the locking bolt of a corresponding 70 or appropriate small locker be withdrawn.

Considering first the means used to this end in connection with the lockers located opposite as contradistinguished from above the large locker,—a metal plate forming a 75 slide is provided and comprises a flat central portion 61 and outwardly extending wings 62 located near the bottom. Two flat lugs 63 are stamped from the material and bent to the right angle position shown and these lugs have each a central aperture 64. The slide is in the form of a handle having legs 65 which extend through two slots 66 in the facing. These legs are connected by bolts 67 with the lugs 64 of the slides, the body 61 80 of the plate lying against the inner surface of the facing. The lock bar 43 is provided with a number of outwardly extending lugs 68, one of which is disposed above the adjacent wing 62 of each such slide, and the parts 85 are so arranged that the other wing 62 is normally disposed just beneath the bolt of the companion lock of the small locker, so that when the lock is locked the slide may not be raised by reason of the fact that the lock 90 bolt extends across the necessary upward path of travel of the slide 61, if effort be made to raise the slide by lifting the handle. When, however, the bolt is withdrawn the slide may then be raised and the appropriate 95 wing 62 of the slide engaging beneath its co-operating lug 65 of the lock bar causes the lock bar to lift and permits the large locker to be opened. Since the lugs 68 are disposed above the several wing slides of the several 100 manipulative devices the lock bar may be moved under the action of any one of these devices without affecting the position of the others, the lugs above the quiet manipulative devices merely rising away from them in 105 this action.

Additional means are provided and a slightly different arrangement made adjacent the two upper lockers since two lock bolts are extended into operative position at 110 the same vertical height and the withdrawing of either one of which must permit opening to the large locker. At this location the slide is secured to the manipulative device in inverted position, that is with the wings 115 62 located above the lock bolts. The slide is secured as before by bolts 69 extending through the lugs 63. The end of the slide 61 is bent out as indicated at 71 to right angle position and the upper end of the lock bar is 120 turned over into the form of a lip 72 which rests upon the lug or shelf provided by the bending over of the slide 61. In this upper slide a hole 73 is provided between the lugs 63. A swinging member 74 is provided and 125 130

has a central large opening 75 through which the lower lug connection 63 extends. This swinging member is pivoted to the slide by a rivet or bolt 76 passing through the opening 5 73 in the slide and through a companion opening 77 in the swinging member. This swinging member has two outwardly extending wings 78 and the device is of tapered form so that the wings are both inclined. The parts 10 are so arranged that the upper ends of the wings are disposed beneath the normal positions of the locking bolts of the two small upper lockers, and when both these bolts are in locking position, the inward movement of 15 the handle of this upper manipulative device is prevented by the conjoint engagement of the two locking bolts of the small locks with the two tops of the wings. When, however, one of these two locking bolts is 20 withdrawn, the handle may be raised to unlock the large locker, the pivoted member swinging under an action of the locking bolt remaining in locked position in sufficient amount to permit the lifting of the locking 25 bar the required distance.

It is thought that the invention and many of its attendant advantages will be understood from the foregoing description, and it will be apparent that various changes may 30 be made in the form, construction and arrangement of the parts without departing from the spirit and scope of the invention or sacrificing all of its material advantages, the form hereinbefore described being 35 merely a preferred embodiment thereof. It will be obvious also that the invention is applicable to any use involving the control of one lock by another.

I claim:

40 1. In a structure of the character described the combination of a number of relatively small lockers and a relatively larger locker, appropriately arranged individual locking means for locking each of the small 45 lockers and locking means for the large locker operable from the outside of the locker and means for preventing operation of the locking means of the large locker when all of the locks of the smaller lockers 50 are in locked position.

2. In a structure of the character described the combination of a number of relatively small lockers and a relatively larger locker appropriately arranged with respect 55 to the small lockers, locks for the small lockers, a lock for the large locker, and devices controlling the operation of the lock of the large locker and in turn controlled by the locks of the small lockers.

60 3. In a structure of the character described the combination of a number of small lockers and a large locker, appropriately arranged manipulative devices without the lockers for unlocking said lockers, a manipulative device for the large locker being

held in inoperative relation with the lock of said locker by the lock of the small locker when in locked position.

4. In a structure of the character described the combination of a plurality of 70 small lockers and a relatively larger locker, appropriately arranged locks for said large and small lockers and manipulative devices for the lock of said large locker in number corresponding to the number of locks for 75 the smaller lockers and located outside the lockers and controllable thereby to prevent unlocking of the large locker by a manipulative device while a corresponding lock of the small locker is in locked position. 80

5. In a structure of the character described the combination of a plurality of small lockers and a relatively larger locker, doors for the small lockers and a lock for the door of the larger locker, manipulative 85 devices for the door of the large locker corresponding in number to the number of small lockers and means for locking each manipulative device in inoperative relation with respect to the lock of the large locker 90 under predetermined conditions.

6. In a structure of the character described the combination of a plurality of small lockers and a relatively larger locker appropriately arranged, a locking member 95 for the large locker, manipulative devices for said locking member in number equal to the number of small lockers each adapted upon movement to unlock the door of the large locker, said locking member of the 100 large locker having an independent movement under an action of the manipulative device while other manipulative devices are at rest.

7. In a structure of the character described the combination of a plurality of small lockers and a relatively large locker approximately arranged, a locking member for the large locker, manipulative devices for said locking member in number equal 105 to the number of small lockers and each arranged adjacent a small locker, said manipulative device having a member held against movement by the locking bolt of said small locker when in locked position. 110

8. In a structure of the character described the combination of a plurality of small lockers and a large locker appropriately arranged, a locking member for said large locker, a pair of locking members for a pair of smaller lockers arranged with the locking bolts extending toward each other and a manipulative device for the locking member of said large locker, said manipulative device comprising a member restraining movement of said manipulating device when both the said locks of the smaller lockers are in locked position. 115

9. In a structure of the character described the combination of a plurality of 120

- small lockers and a large locker appropriately arranged, a locking member for said large locker, a pair of locking members for a pair of smaller lockers arranged with the locking bolts extending toward each other and a manipulative device for the locking member of said large locker, said manipulative device comprising a member restraining movement of said manipulating device 10 when both the said locks of the smaller lockers are in locked position, and having a swinging movement to permit action of the manipulative device when one of said bolts is withdrawn.
- 15 10. In a mechanism of the character described, the combination of one locking mechanism having manipulative means, and

a second locking mechanism when in locked position acting to prevent manipulation of the manipulative means whereby to retain 20 both locking mechanisms in locked condition.

11. In a structure of the character described, the combination of two lockers each having locks and one of said locks having 25 a part controlling the lock movement of the other.

12. In a structure of the character described, the combination of two lockers, a lock for each locker one of said locks having 30 an operative device restrained against movement by the lock bolt of the other.

WALTER N. VANCE.
